tion of Delaware

Application November 26, 1941, Serial No. 420,559

10 Claims. (Cl. 230—24)

My present invention relates to the control of compressing means for compressing a gaseous medium, particularly compressing means adapted to compress a refrigerant in refrigerating or air conditioning systems. The invention specifically comprises an improvement upon the compressor unloading means disclosed and claimed in my Patent No. 2,185,473, issued January 2, 1940, but, as will presently appear, the invention has application in a variety of forms of compressors.

One object of the invention is to provide means for preventing the loading of a compressor until a predetermined time interval after commencement of cyclical operation of the compressing mechanism. A compressing mechanism usually comprises a suction valve and a discharge valve operating in conjunction with a piston, which parts go through cycles of operation including the drawing of gas through the suction valve, compressing thereof by the piston and discharge of the compressed gas through the discharge valve. A compressor may comprise a single piston and set of valves or it may comprise a plurality of pistons each with its own set of valves. In the present disclosure the compressor comprises a plurality of reciprocating pistons, each with its own set of valves, located radially about the compressor crankshaft. In accordance with the present invention a single compressing means or a plurality of compressing means may be controlled to prevent the application of load to the prime mover, i. e., to prevent the compression of the gaseous medium, until a predetermined length of time after commencement of cyclical operation of the compressing means.

The principal purpose of the present invention is to permit the application of an inexpensive type of motor, or other prime mover, to the driving of gaseous medium compressors. By preventing the loading of the compressor, or at least a portion thereof, until after the compressor has attained full speed a low starting torque, low starting inrush electric motor may be employed, or an internal combustion engine of sufficient horsepower to drive the fully loaded compressing means at full speed, but of insufficient horsepower to operate the fully loaded compressing means at less than full speed, may be employed. Aside from the saving in material and initial cost thus effected, there is a decided advantage in the operating expense since the current consumption or fuel consumption of the prime mover is materially reduced. This is of special importance in some localities where the consumer charge for

use of electric current is based upon the starting inrush current peak. If the starting inrush is just sufficient to overcome the inertia of the rotor and operating parts of the compressing means, the stand-by charge or peak load charge may be materially reduced.

A further object of the present invention is to provide means automatically and instantaneously to render the compressing means inoperative until a predetermined time interval after stoppage of the prime mover. This is of particular importance in certain installations wherein a repeating starter may be employed, such as, for example, in a compressor connected to an internal combustion engine provided with an automatically repeating starter mechanism which is designed to operate a plurality of times in spaced succession provided the internal combustion engine does not immediately start. Such mechanisms fail to take into account the fact that the reason for inability to start the internal combustion engine might be the inability of the starting motor to carry the compression load as well as to overcome the inertia of the internal combustion engine and the compressor. In the present invention, upon cessation of cyclical operation of the compressing means, the compressing means is immediately rendered ineffective to compress the gaseous medium and remains in such ineffective state for a predetermined length of time which may be such as to exceed the length of time required for the engine to reach full speed.

A further object of the present invention is to safeguard the rotor or other portions of electric motors employed to operate refrigerant compressing means. It sometimes happens, such as occasionally caused by lightning striking the power lines, that the rotor is momentarily locked against rotation due to a reversed current surge greater than the normal current supply to the motor. If, after passage of the lightning surge, the rotor is expected immediately to pick up the full compression load the windings of the motor may be so overloaded as to cause the insulation to burn and cause a short-circuit. A similar situation exists with regard to the human element in that an untrained operator or some unauthorized person may flick the starting switch on and off in rapid succession. In either event or in any other similar event, the present invention is designed to relieve the motor of the compression load until the motor has been given the opportunity to achieve full speed.

These and other objects and advantages of the present invention will be more readily apparent

to those skilled in the art upon inspection of the accompanying drawings taken in connection with the following specification wherein like numerals refer to like parts throughout.

In the drawings.

Fig. 1 discloses a compressor embodying a plurality of compressing means, as disclosed in my Patent No. 2,185,473, issued January 2, 1940, the compressor being mounted in a condensing unit for a refrigerating system and driven by an electric motor;

Fig. 2 is a longitudinal, vertical section taken through the compressor of Fig. 1, certain parts of the sectional view being on irregular planes for the purpose of complete disclosure;

Fig. 3 is a vertical section through a time delay relay comprising a portion of the present invention;

Fig. 4 is a vertical section through a valve comprising a portion of the present invention.

Fig. 5 is an axial section through one of the compressing cylinders and pistons; and

Fig. 6 is a horizontal section through the master valve and master valve controlling means of the compressor.

The usual condensing unit for a refrigerating system comprises a compressor 10 driven by a prime mover, in this case an electric motor 11, and a condenser 12 into which the compressed refrigerant is discharged by the compressor and from which the cooled refrigerant may be withdrawn through a discharge line 13 having connection to the cooling portion of the refrigerating or air conditioning system (not shown) from which the expanded refrigerant is returned to the compressor through a suction pipe 14.

It is to be appreciated that the compressor 10 may comprise an air compressor drawing air from the atmosphere through an inlet 14 and discharging the compressed air into a receiver mounted in the position of the condenser 12.

The compressor 10 comprises a plurality of cyclically operating compressing means each including a piston 20, a suction valve 21, and a discharge valve 105 mounted in a discharge valve head 22, each of the pistons 20 being operated through connecting rods 23 mounted upon the crankpin 24 of a crankshaft 25 connected to the prime mover 11. Cyclical operation of the compressing means would normally commence instantaneously with the operation of the prime mover to draw a gaseous medium from the interior of the crankcase through the suction valve 21, to compress the same and to discharge the compressed gaseous medium through the discharge valve as fully explained in the aforesaid patent.

The compressor of the present invention is lubricated by a pump 30 driven through gears 31 and 32, the latter of which is mounted on a shaft having driven connection to the crankshaft 25 through the medium of a pin and slot connector 33. The pump, therefore, operates simultaneously and coextensively with cyclical operation of the compressing means. The pump, as fully explained in the aforesaid patent, draws lubricant from the crankcase and forces it through an outlet 34 into a plurality of passages having communication with the bearings and other wearing surfaces of the compressor.

Lubricant under pressure is also forced by the pump through a passage 35 into a master valve 36 from which the lubricant may be distributed to various cylinder unloading means through the operation of the master valve, which is under

control of a metallic bellows 37 influenced by the suction pressure existing within the crankcase of the compressor 10. Lubricant may be passed by the master valve 36 into one of several connections 38 each leading to a space 39 containing a piston 40. The piston 40 is connected by means of a piston rod 41 to a yoke 42 surrounding the cylinder wall 43 in which the piston 20 operates. The end of the yoke is provided with a roller adapted to climb a ramp 44 in order to raise a ring 45 surrounding the cylinder 43 and which is provided with a plurality of vertical rods 46. When fluid pressure is applied through the connection 38 against the piston 40 the roller in yoke 42 is lowered down the ramp 44 and the rods 46 are lowered to the position illustrated, in which position the suction valve 21 is seated so that the compressing means is loaded or will compress the gaseous medium. Upon release of fluid pressure from against the piston 40 a spring 47 surrounding the piston rod 41 forces the piston 40 outward and causes the roller in the end of yoke 42 to climb the ramp 44, thereby raising the ring 45 and causing the rods 46 to raise the suction valve 21 from its seat. As long as this condition exists the compressing means is unloaded since gas drawn into the cylinder through the suction valve would be forced back through the suction valve into the crankcase without compression thereof.

Reference to Figs. 5 and 6 will more completely clarify the foregoing, the figures more completely disclosing details of the mechanism. Fig. 5 shows that rods 46 are lowered by the combined thrust of springs 100 on the rods 46 and springs 101 on the suction valve 21. Valve 21 may open when the pressure within cylinder 43 is lower than the pressure existing in suction manifold 102, thus permitting gas to enter the cylinder through ports 103. More gas may enter through ports 104 when the piston is fully retracted. When the piston 20 is thrust outwardly the valve 21 closes and discharge valve 105 opens against the thrust of springs 106 held in discharge valve head 22, thus permitting escape of compressed gas into the discharge manifold through port 107. The suction manifold is connected to the space surrounding bellows 37 (Fig. 6) through ports such as port 110 (Fig. 5). Thus bellows 37 may contract or expand as the load on the refrigerating system, and hence the suction pressure, varies. Bellows 37 may fully contract against the end of guide-limit tube 111, in which position all cylinders are loaded, or may fully expand, in which position all cylinders are unloaded. The bellows is connected to limit rod 112, which extends outward and is provided with an adjustment nut 113 which is adapted to strike the end of a tube 114 to limit the extent of movement of bellows 37 and hence limit the number of cylinders which may be unloaded. Tube 114 is slotted and the slot guides a regulator member 115 which holds one end of a regulator spring 116, the other end of which bears against the inner end of bellows 37. The position of member 115 may be set by nut 117 and locknut 118, threaded onto tube 114, to regulate the pressure of spring 116 and hence determine the range of pressures at which the bellows expands or contracts. Bellows 37 is also connected to a rod 120 pivotally connected to a rocker arm 121 mounted on the body of master valve 36 and pivotally connected to the master valve rod 50. The master valve rod 50 is thus caused to move in ratio to the movements

of bellows 37. This movement is limited to short steps by a spring-pressed ball 122 bearing in grooves 123 in rod 50. At each step of the valve rod one of the tubes 38 is thus connected to or disconnected from the source of fluid pressure through the valve slots as shown.

Complete details and a more detailed explanation of the individual cylinder unloading means may be found in the aforesaid patent, which also discloses more complete details and explanation of the following operation thereof. The selection of the pistons 40 which are to have fluid pressure applied thereto to cause unloading of the compressing means associated therewith is subject to a condition of the gaseous medium being compressed, such as the suction pressure existing within the crankcase of the compressor. This is effected by the metallic bellows 37 which may expand or contract to cause movement of the master valve rod 50 in the master valve 36. Movement of the master valve rod 50 causes connection of one or more of the connecting tubes 38 to the source of fluid pressure so as to cause loading of the individual compressing means to which the tubes 38 lead, or disconnection there with resultant unloading. Some or all of the tubes 38 may be disconnected, or, vice versa, some or all of the tubes 38 may be connected to the source of fluid pressure.

When the prime mover stops in a refrigerating system the pressure in the crankcase increases, such increase soon causing complete collapse of the bellows 37 and complete connection of the unloading means to the source of fluid pressure. As soon as the prime mover starts cyclical operation of the compressing means again, simultaneous operation of the pump 30 commences. For the first few rotations of the crankshaft 25 insufficient fluid pressure is created by the pump 30 to cause movement of the pistons 40 and resultant loading of any of the compressing means. In a very short period of time, such as one-fifth of a second when the prime mover is operated by 60-cycle current at 1,750 R. P. M., sufficient fluid pressure will be generated by the pump to cause movement of all of the pistons 40 and loading of all of the compressing means. Thereafter, as the suction pressure of the refrigerating system is reduced, the bellows 37 expands to disconnect one or more of the tubes 38 and cause unloading of one or more of the compressing means so that the capacity of the compressor automatically varies in accordance with the load on the refrigerating system; hence the motor consumes power variably in proportion to the load on the refrigerating system.

In most installations the short period of time required to build up sufficient fluid pressure, one-fifth of a second in the above example representing 12 cycles of alternating current, is sufficient for the motor to overcome its own inertia and the inertia of the compressing means and attain sufficient speed to carry the full compressing load. The present invention is designed to take care of the unusual installation or to make absolutely certain that the usual installation will function, and to reduce the starting torque in any installation.

The present invention comprises the addition to the foregoing system of a time delay mechanism to prevent connection of the fluid pressure creating means to the fluid pressure operated loading means until a predetermined safe length of time after commencement of cyclical operation of the compressing means. The time delay

means comprises a time delay relay 55 and a by-pass valve 56 operating to break the connection between the pump 30 and the master valve 36 until it is absolutely certain that the prime mover is operating at full speed. The time delay relay 55 preferably comprises a solenoid 57, the windings of which are connected by wires 58 to the power leads of the prime mover, in the example shown to two wires of a three-phase system. The core 60 of the solenoid is provided with a piston 61 operating in a dash-pot 62, the piston 61 being provided with a metering orifice 63 and a check valve 64 so arranged as to open upwardly. Upon energization of the solenoid 57 the core 60 will be drawn upward, the rate of travel of the core being held to that permitted by the escape of fluid from above the piston 61 through the metering orifice 63. The core 60 has sufficient travel to operate an insulated plunger 65 which closes contacts 66 to complete a circuit including a second solenoid 67 which draws current from the power leads to the prime mover and which operates the by-pass valve 56. The closing of contacts 66 is delayed a predetermined interval of time depending upon the rate of escape of the fluid in the dash-pot 62 after initial energization of the prime mover 11. On the other hand, opening of the contacts 66 may be substantially instantaneous due to the rapid escape of the fluid through the check valve 64 when the solenoid is deenergized. It is to be appreciated that the present disclosure is relative schematic, there being many such devices for accomplishing timed closing of the contacts 66 and substantially instantaneous opening of the contacts 66.

The by-pass valve 56 preferably comprises a core 70 attached to a valve plunger 71 provided with an opening 72 of considerable length. The body 73 of the valve is provided with three passages 74, 75 and 76 in vertical alignment. The valve 56 is attached to the crankcase cover 77, and the openings 74, 75, and 76 are aligned with matching openings 78, 79, and 80, respectively, in the cover 77. The opening 78 leads directly into the interior of the compressor so that fluid passing therethrough drains back to the pump 30. The opening 79 is connected to a tube 81 which comprises the supply tube to the master valve 36, and the opening 80 is connected to a tube 82 which communicates with the passage 35 leading to the discharge side of the pump 30.

When the solenoid 67 is deenergized due to opening of the contacts 66, the valve plunger 71 is in the position shown in Fig. 4 so that the output of the pump is blocked from the master valve 36. As soon as the dash-pot device has closed the contacts 66, the solenoid 67 is energized to raise the plunger 71 in order to connect tube 81 to tube 82, thus causing the immediate application of fluid pressure to the master valve 36. Upon such application of fluid pressure all of the pistons 40 will be operated against the springs 47 to load all of the compressing means since the master valve will have been moved to entire connecting position by collapse of the metallic bellows 37. The arrangement of the plunger 71 is such that immediate discontinuance of power to the prime mover or reversal of current thereto would result in immediate unloading of all of the compressing means since the plunger 71 would immediately drop, thus connecting the master valve to the interior of the crankcase through the opening 78 and permitting the lubricant therein to flow out and permit the springs

47 to operate the unloading means. Reapplication of current in the next moment would not cause reloading of the compressor until after the dash-pot device had been overcome.

As fully explained in the aforesaid patent the operation of the master valve 38 may be accomplished by some other condition of the gaseous medium being compressed, such as the pressure in the receiver into which the compressed gas is discharged. It should be apparent to those skilled in the art that such a modification would permit the application of the present invention to an air compressing mechanism.

It should be obvious to those skilled in the art that the present invention may be applied to the combination of a compressor and an internal combustion engine of the type having automatic starting means, such as by causing the energization of the solenoid 57 to occur simultaneously with application of current to the internal combustion engine starting motor.

It should be apparent to those skilled in the art that many other modifications in the invention and application of the present invention, as well as in the details thereof may be realized from the teachings of the present disclosure. All such modifications as come within the scope of the following claims are considered a part of my invention.

I claim:

1. A compressor comprising a prime mover, a cyclically operating compressing means driven by said prime mover and adapted normally to compress a gaseous medium at each cycle of operation; means to vary the compressing capacity of said compressing means from no capacity to full capacity automatically in response to a condition of the gaseous medium including fluid pressure creating means effective simultaneously with cyclical operation of said compressing means, fluid pressure operated means for effecting the loading of said compressing means to full capacity when connected to said fluid pressure creating means, and spring means for effecting the unloading of the compressing means to no capacity when said fluid pressure operated means is disconnected from said fluid pressure creating means; and a time delay mechanism preventing the application of fluid pressure created by said fluid pressure creating means to said fluid pressure operated means until a predetermined length of time after commencement of cyclical operation of said compressing means to delay the loading of said compressing means for sufficient time to permit said prime mover to attain operating speed.

2. A compressor comprising a prime mover, a cyclically operating compressing means driven by said prime mover and adapted normally to compress a gaseous medium at each cycle of operation; means to vary the compressing capacity of said compressing means from no capacity to full capacity automatically in response to a condition of the gaseous medium including fluid pressure creating means effective simultaneously with cyclical operation of said compressing means, fluid pressure operated means for effecting the loading of said compressing means to full capacity when connected to said fluid pressure creating means, spring means for effecting the unloading of the compressing means to no capacity when said fluid pressure operated means is disconnected from said fluid pressure creating means, and a master valve between said fluid pressure creating means and said fluid pressure operated means responsive to a condition of the gaseous medium for

connecting or disconnecting said fluid pressure creating means and said fluid pressure operated means; and a time delay mechanism preventing the passage of fluid under pressure from said fluid pressure creating means through said master valve until a predetermined length of time after commencement of cyclical operation of said compressing means even though said master valve may be open to delay the loading of said compressing means for sufficient time to permit said prime mover to attain operating speed.

3. A compressor comprising cyclically operating compressing means adapted normally to compress a gaseous medium at each cycle of operation; means to vary the compressing capacity of said compressing means from no capacity to full capacity automatically in response to a condition of the gaseous medium including fluid pressure creating means effective simultaneously with cyclical operation of said compressing means, fluid pressure operated means for effecting the loading of said compressing means to full capacity when connected to said fluid pressure creating means, spring means for effecting the unloading of the compressing means to no capacity when said fluid pressure operated means is disconnected from said fluid pressure creating means, and a master valve between said fluid pressure creating means and said fluid pressure operated means responsive to a condition of the gaseous medium for connecting or disconnecting said fluid pressure creating means and said fluid pressure operated means; and a time delay mechanism preventing the passage of fluid under pressure through said master valve until a predetermined length of time after commencement of cyclical operation of said compressing means even through said master valve may be open, said time delay mechanism including a solenoid adapted to be energized upon commencement of cyclical operation of said compressing means, a switch adapted to be closed by said solenoid when energized, and a dash-pot delay mechanism causing slow action of said solenoid.

4. A compressor comprising cyclically operating compressing means adapted normally to compress a gaseous medium at each cycle of operation; means to vary the compressing capacity of said compressing means from no capacity to full capacity automatically in response to a condition of the gaseous medium including fluid pressure creating means effective simultaneously with cyclical operation of said compressing means, fluid pressure operated means for effecting the loading of said compressing means to full capacity when connected to said fluid pressure creating means, spring means for effecting the unloading of the compressing means to no capacity when said fluid pressure operated means is disconnected from said fluid pressure creating means, and a master valve between said fluid pressure creating means and said fluid pressure operated means responsive to a condition of the gaseous medium for connecting or disconnecting said fluid pressure creating means and said fluid pressure operated means; and a time delay mechanism preventing the passage of fluid under pressure through said master valve until a predetermined length of time after commencement of cyclical operation of said compressing means even though said master valve may be open, said time delay mechanism including a solenoid adapted to be energized upon commencement of cyclical operation of said compressing means, a switch adapted to be closed by said solenoid when energized, a

dash-pot delay mechanism causing slow action of said solenoid, and a solenoid operated valve between said fluid pressure creating means and said master valve adapted to be energized upon closing of said switch to complete the fluid connection of said fluid pressure creating means and said fluid pressure operated means.

5. A compressor comprising loading means dependent upon fluid pressure for activating power, fluid pressure creating means operated simultaneously with cyclic operation of the compressor for creating such fluid pressure, and time delay means for preventing the application of fluid pressure to said loading means for a predetermined length of time after commencement of operation of said fluid pressure creating means including a valve between said fluid pressure creating means and said loading means and electrical means for opening said valve to permit the application of fluid pressure to said loading means, said electrical means comprising a first solenoid for opening said valve when energized, a switch in series with said first solenoid for permitting current to flow through said first solenoid when closed, and a second solenoid for closing said switch.

6. A compressor comprising loading means dependent upon fluid pressure for activating power, fluid pressure creating means operated simultaneously with cyclic operation of the compressor for creating such fluid pressure, and time delay means for preventing the application of fluid pressure to said loading means for a predetermined length of time after commencement of operation of said fluid pressure creating means including a valve between said fluid pressure creating means and said loading means and electrical means for opening said valve to permit the application of fluid pressure to said loading means, said electrical means comprising a first solenoid for opening said valve when energized, a switch in series with said first solenoid for permitting current to flow through said first solenoid when closed and a second solenoid for closing said switch, said second solenoid being included in a circuit adapted to be energized simultaneously with commencement of cyclical operation of said compressor.

7. A compressor comprising loading means dependent upon fluid pressure for activating power, fluid pressure creating means operated simultaneously with cyclic operation of the compressor for creating such fluid pressure, and time delay means for preventing the application of fluid pressure to said loading means for a predetermined length of time after commencement of operation of said fluid pressure creating means including a valve between said fluid pressure creating means and said loading means and electrical means for opening said valve to permit the application of fluid pressure to said loading means, said electrical means comprising a first solenoid for opening said valve when energized, a switch in series with said first solenoid for permitting current to flow through said first solenoid when closed, a second solenoid for closing said switch, said second solenoid being included in a circuit adapted to be energized simultaneously with commencement of cyclical operation of said compressor, and means for delaying the effectiveness of said second solenoid to close said switch for a predetermined interval of time after becoming energized.

8. A compressor comprising loading means dependent upon fluid pressure for activating power,

fluid pressure creating means operated simultaneously with cyclic operation of the compressor for creating such fluid pressure, and time delay means for preventing the application of fluid pressure to said loading means for a predetermined length of time after commencement of operation of said fluid pressure creating means including a valve between said fluid pressure creating means and said loading means and electrical means for opening said valve to permit the application of fluid pressure to said loading means, said electrical means comprising a first solenoid for opening said valve when energized, a switch in series with said first solenoid for permitting current to flow through said first solenoid when closed, a second solenoid for closing said switch, said second solenoid being included in a circuit adapted to be energized simultaneously with commencement of cyclical operation of said compressor, and means for delaying the effectiveness of said second solenoid to close said switch for a predetermined interval of time after becoming energized including a dash-pot device.

25 9. A compressor comprising loading means dependent upon fluid pressure for activating power, fluid pressure creating means operated simultaneously with cyclic operation of the compressor for creating such fluid pressure, and time delay means for preventing the application of fluid pressure to said loading means for a predetermined length of time after commencement of operation of said fluid pressure creating means including a valve between said fluid pressure creating means and said loading means and electrical means for opening said valve to permit the application of fluid pressure to said loading means, said electrical means comprising a first solenoid for opening said valve when energized, a switch in series with said first solenoid for permitting current to flow through said first solenoid when closed, a second solenoid for closing said switch, said second solenoid being included in a circuit adapted to be energized simultaneously with commencement of cyclical operation of said compressor, and means for delaying the effectiveness of said second solenoid to close said switch for a predetermined interval of time after becoming energized including a dash-pot device; and means for substantially instantaneously unloading said compressor by removal of fluid pressure from said loading means upon cessation of cyclical operation of the compressor.

10. A compressor comprising loading means dependent upon fluid pressure for activating power, fluid pressure creating means operated simultaneously with cyclic operation of the compressor for creating such fluid pressure, and time delay means for preventing the application of fluid pressure to said loading means for a predetermined length of time after commencement of operation of said fluid pressure creating means including a valve between said fluid pressure creating means and said loading means and electrical means for opening said valve to permit the application of fluid pressure to said loading means, said electrical means comprising a first solenoid for opening said valve when energized, a switch in series with said first solenoid for permitting current to flow through said first solenoid when closed, a second solenoid for closing said switch, said second solenoid being included in a circuit adapted to be energized simultaneously with commencement of cyclical operation of said compressor, and means for delaying the effectiveness of said second solenoid to close said

switch for a predetermined interval of time after becoming energized including a dash-pot device; and means for substantially instantaneously unloading said compressor by removal of fluid pressure from said loading means upon cessation of cyclical operation of the compressor including a connection between said loading means and the

interior of said compressor adapted to be opened upon deenergization of said first solenoid, and a check valve in said dash-pot device permitting rapid opening of said switch upon deenergization of said second solenoid.

CHARLES R. NEESON.
